UNITED STATES PATENT OFFICE.

MARCUS B. BEHRMAN, OF NEW YORK, N. Y., ASSIGNOR TO THE LOX SEAL CORPORATION OF BROOKLYN, NEW YORK, A CORPORATION OF NEW YORK.

PILE-WIRE CUTTER.

Application filed May 7, 1926. Serial No. 107,334.

My present invention relates to pile wires, and has particular reference to the blade holder which is associated therewith.

The use of pile wire cutters in the manufacture of pile fabrics is beset with many difficulties. One of these has its origin in the necessity for constantly replenishing the blades which have become dulled. For this purpose, it is customary to provide the blades in the form of flexible wafers, and to provide the blade holders with suitable means for firmly holding the blades and at the same time permitting ready removal thereof.

It is one of the objects of the present invention to provide means in association with the blade holder for facilitating the insertion and removal of blades, and for assuring firm retention of the blade after it has been placed into use.

Where I have used blade holders which comprise channel portions for receiving the blades, I have found it desirable to plug or block portions of the channel for the purpose of forming a recess into which an end of the blade may be inserted. It is an object of the present invention to accomplish this purpose by means of a construction which is at one time inexpensive, simple and efficient.

In accordance with this object of the invention, I have found it extremely satisfactory to produce this result by the insertion of a plug, suitably configured, into an end portion of the channel. More particularly, the plug is so arranged and constructed as to provide an overhanging end portion or wall beneath which an end of the cutting blade may be inserted.

Another one of the difficulties encountered in the use of pile wires is based upon the different requirements of different looms or mills. More particularly, in certain cases a pile wire of a certain height is used or required, and in other cases, pile wires having a different height are necessary. It has therefore been necessary heretofore to provide blade holders, either as attachments for the pile wires or as integral parts thereof, in varying sizes; and more particularly, it has been necessary to provide blade holders of different heights. Inasmuch as the cutting blade must project out of the blade holder by a proper predetermined amount, it has been necessary to provide not only holders of different heights, but also blades of different sizes. The reason for this will

be obvious. Where blade holders are used which comprise U-shaped channels formed by doubling over a substantially flat blank, an increase in the height of the blade holder will produce an increase in the depth of the channel. As a result, a blade having a greater depth must be employed with the latter type of blade holder, so that the blade will still be enabled to project a proper distance from the blade holder.

It is an object of the present invention to overcome this difficulty and to permit the utilization of a standardized blade with all heights of blade holders. Accordingly, a feature of the invention lies in providing means for rendering each of a series of blade holders available for use with a standard blade, thereby increasing the efficiency of use, and effecting great economies in the manufacture of blade holders.

In accordance with the embodiment herein disclosed, I provide an insert or plug which is capable of being associated with the blade holder so as to reduce the effective depth of the channel therein. More particularly, I provide a series of these plugs, the plugs varying in size in accordance with the varying heights of blade holders, so that any selected blade holder may be standardized by the association therewith of a properly selected insert.

For the attainment of the foregoing objects and such other objects as may herein-after appear or be pointed out, I have illustrated my invention in the accompanying drawings in which:

Fig. 1 is a side elevation of a pile wire blade holder of relatively small height, having associated therewith a blade which may, for illustrative purposes, be considered standard;

Fig. 2 is a similar view of the blade unassociated with any holder;

Fig. 3 is a perspective view of a blade holder having a relatively greater height, and having the standard blade associated therewith in accordance with the present invention; and

Fig. 4 is a cross-sectional view taken along the line 4-4 of Fig. 3.

Referring to the drawings, it will be observed that I have shown a blade holder 10 having a forward enlarged spoon portion 11, the purpose of which will be well-known to those skilled in the art. The blade holder

shown is of the type which is constructed of a substantially flat blank doubled-over along a longitudinal line 12 to form a U-shaped blade receiving channel 13.

5 The blade which I prefer to use is of the flexible wafer type having a bottom edge 14, a cutting edge 15 disposed at an angle to the edge 14, and a forward edge 16 which completes a generally triangular figure. 10 The blade is associated with a holder by positioning its rear end, or foot 17, under an overhanging wall of the character hereinbefore referred to. The other end 16 is constructed in a manner which permits co-operation thereof with a suitable tab 18 provided on the spoon portion 11. More particularly, this tab 18 is struck up out of the spoon portion 11 into the path of the channel, and it comprises a transverse edge 19, and upper and lower edges 20 and 21 respectively, each of the edges 19, 20, and 21 having been formed by cutting proper slits through the spoon portion 11. For a purpose presently to be understood, the slit 20 is preferably made shorter than the slit 21. For proper co-operation with the tab 18, the end 16 of the blade is constructed with a cut-out portion which provides an end edge 22 parallel to the edge 16 but offset with respect thereto, and a connecting edge 23 substantially parallel to the edge 14. After the foot 17 of the blade has been properly positioned, the entire blade is flexed so that the end 16 will spring into place beneath the tab 18. More particularly, the edge 22 will be caught by the end of the slit 20, while the edge 23 will encounter the edge 21 and prevent upward movement of the blade after it has been positioned. 35

40 I shall now describe the construction which permits engagement of the foot 17 of the blade. The general purpose is to provide an overhanging wall 24 (Fig. 1) beneath which the foot 17 may rest. This 45 overhanging wall assumes a general direction extending from the rear base of the channel upwardly and forwardly to the open end of the channel. In Fig. 3 I have shown one method of achieving this result. I provide a wedge-shaped insert 25 having an under-edge 26 which may be said to be beveled. More specifically, the under-edge 26 is arranged at an angle to the axis of the channel. Thereby, only a portion of the 55 channel is effectively blocked by the wedge 25. This portion is the outer portion of the channel, the inner portion being unblocked by the insert and constituting an undercut recess. The member 25 may be secured in 60 position by any suitable means, as by welding, soldering, or otherwise. Where a member of this type is used, I prefer to shape its outer edge in a manner which will make it conform to the upper edge of the blade holder. The inclination of the under-edge

26 is optional, as may be well understood. As to the employment of the insert 25 to form the overhanging wall, this application is a continuation of my earlier filed application No. 752,146 filed November 25, 1924. 70

Referring now to Fig. 3, I have shown a standardized blade associated with a blade holder having a height greater than that of the blade holder of Fig. 1. This blade holder comprises a similar spoon portion 11', tab 18', and channel portion 13'. It will be observed, however, that the depth of the channel is, in this case, much greater than that of Fig. 1. In fact, the depth of the channel is too great, with respect to the blade depth, to permit proper positioning of the blade within the channel, so as to have the proper amount of projection out of the channel. For the purpose of rendering this blade holder available for use with the standardized blade, I provide a plugging member 33 in the form of a strip, this member being insertable into the channel 13' so as to provide a raised bottom therefor. By the proper selection of insert 33, the new bottom may be provided at a predetermined raised point with respect to the bottom of the holder. The blade may be made to rest upon this substitute bottom in lieu of the original channel bottom. The insert 33 may be suitably positioned by soldering, welding, or merely by frictional engagement within the channel. It will be understood that its application need not necessarily affect the overhanging wall construction hereinabove described. The latter may be provided upon the basis of the newly formed bottom. That is, where a wedge member is employed, it may be preferably associated within the channel so as to extend only to the insert 105 33. This, however, is not essential, as will be understood.

It will be obvious that various changes in the details herein described and illustrated for the purpose of explaining the 110 nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. A pile wire cutter comprising a U-shaped blade-receiving channel, a removable blade for insertion thereinto, and a plug carried entirely within the channel at one end thereof and configured to provide an undercut recess within which one end of the blade may be made to rest. 125

2. A pile wire cutter comprising a channelled blade holder, a blade removably insertable into said channel, and a beveled

insert carried in the channel and partially blocking an end thereof, said insert being configured to provide an undercut recess thereunder, into which recess an end of the 5 blade may be inserted.

3. A pile wire cutter comprising a channeled blade holder, and a wedge-shaped insert carried in one end of the channel, said insert having its underside angularly disposed with respect to the channel bottom.

4. A pile wire cutter comprising a U-shaped blade holder, and an insert carried in one end thereof and so disposed as to block the open portion of the U, the insert 15 being so dimensioned as to be insertable through the open top of the U whereby a recess is provided under the insert into which an end of a blade may be inserted.

5. A pile wire cutter comprising a 20 U-shaped blade-receiving channel, a blade removably insertable thereinto, an insert within the channel and providing a raised bottom therefrom upon which the blade may

be made to rest, and an insert carried in one end of the channel and configured to provide 25 an undercut recess into which an end of the blade may be inserted.

6. A pile wire cutter comprising a channeled blade holder adapted to receive a blade thereon, and means for securing said blade 30 in the channel, said means comprising a rigid plug carried wholly in the channel in fixed association therewith for its entire length to engage one end of the blade and a portion cut up from a wall of the channel 35 to engage the opposite end of the blade.

7. A pile wire knife comprising, in combination, a blade holder presenting a groove in which said blade is received, and insert means received in said groove to provide 40 a raised bottom for the groove and on which the blade can be received and an abutment to overhang one end of said blade.

In witness whereof, I have signed this specification.

MARCUS B. BEHRMAN.
